UNITED STATES PATENT OFFICE.

HAWLEY B. LEFLER, OF GRAND BAYOU, LOUISIANA, ASSIGNEE OF ONE-HALF TO D. E. FRANCE RUSSELL, OF GRAND BAYOU, LOUISIANA.

POLISH-ROD CLAMP.

Application filed September 29, 1922. Serial No. 591,262.

To all whom it may concern:

Be it known that HAWLEY B. LEFLER, a citizen of the United States of America, residing at Grand Bayou, in the parish of 5 Red River and State of Louisiana, has invented new and useful Improvements in Polish-Rod Clamps, of which the following is a specification.

The object of the invention is to provide 10 a simple and efficient clamp for use in supporting the polish rod of a well drilling rig during the application or removal of pump rods and particularly to provide a device of this type whereby the accidental release 15 of the pump rod with its attached string of tools may be prevented to avoid the loss of time and the expense incident to such occurrences in connection with well drilling operations; and with these objects in view 20 the invention consists in a construction and combination of parts of which a preferred embodiment is shown in the accompanying drawings, wherein:—

Figure 1 is a view of a pump rigging of 25 conventional form equipped with a polish rod clamp constructed in accordance with the invention.

Figure 2 is a detail view of the clamp detached.

30 Figure 3 is a detail sectional view of the same.

Figure 4 is a detail sectional view at right angles to the plane of Figure 3.

The clamp 10 which as in the ordinary 35 practice is adapted to be engaged with a follower rod 11 and to rest upon the casing head 12 during the interchange, insertion or removal of pump or drill rods in connection with well drilling and pumping operations, consists of a horizontally U-shaped 40 body portion 13, which may be a casting or forging having a slot 14 extended thereinto from one side edge and terminating in a rounded seat 15 for the reception of a polish 45 or drill rod, and a follower block 16 fitted in said slot and provided at its inner end with a seat 17 which complements the seat 15 to embrace the polish or drill rod fitted therein. The arm portions 13^a of the body 50 member 13 and the follower block are provided with registerable openings 18 and 19 for the reception of a tapered or wedge pin 55 which when driven into place as indicated serves to advance the follower block 20 toward the seat in the body member of the

clamp to compressively engage the rod interposed between the inner end of said block and the seat in the body chamber. The force with which this compression or clamping action may be effected is of course dependent upon the amount to which the pin or wedge is driven into place and may be varied according to the weight of the rods and tools imposed thereon to insure an effective holding of the rod during the operations incident to inserting or removing a section.

In order that there may be an automatic clamping action of the block in the event of a tendency to downward movement of 70 an engaged pump rod or tube the opening 19 in the block is elongated to form a slot extending obliquely to the seat 17 at the inner face of the block. Thus any downward tendency of the block will cause it to move 75 inwardly to increase the transverse pressure on the engaged rod or tube.

Having described the invention, what is claimed as new and useful is:—

1. A polish rod clamp having a transversely U-shaped body member provided with a throat terminating in a seat for the reception of a drill rod, a follower block fitted in the throat of said body member and movable toward and from the seat in the latter, and a tapered or wedge pin transversely engaging registerable openings in said body member and follower block for advancing the latter toward the said seat to clamp a rod interposed between the same 90 and the seat.

1. A polish rod clamp having a transversely U-shaped body member provided with a throat terminating in a seat for the reception of a drill rod, a follower block fitted in the throat of said body member and movable toward and from the seat in the latter, and a tapered or wedge pin transversely engaging registerable openings in said body member and follower block for advancing the latter toward the said seat to clamp a rod interposed between the same and the seat, the inner end of the follower block being provided with a concaved seat to complement that in the body member. 100

3. A polish rod clamp having a transversely U-shaped body member provided with a throat terminating in a seat for the reception of the drill rod, a follower block fitted in the throat of the body member and 110

movable toward and from the seat thereof, said block being provided at its inner end with a seat for cooperating with that in the throat of the body member, and a pin trans-
5 versely engaging registering openings in said body member and follower block, the opening in one of said members being elongated to form a slot disposed in oblique re-

lation to the seat at the inner face of the block to cause an inward movement of the 10 latter coincidentally with the longitudinal movement thereof.

In testimony whereof he affixes his signature.

HAWLEY B. LEFLER.
